UNITED STATES PATENT OFFICE.

WILLIAM H. BAKER, JR., OF CINCINNATI, OHIO.

POWER TRANSMISSION.

Application filed May 26, 1927. Serial No. 194,473.

This invention relates to power transmissions in which the ordinary mounting or supporting wheels of a locomotive-engine, that are ordinarily known as the driving-wheels thereof, are accompanied by a superposed series of relatively-coincident axle-connected auxiliary driving-wheels, the latter being connected by means of crank and reciprocating mechanism with the steam-pistons at the 5 opposite longitudinal sides of the engine, and the prime object of such novel and peculiar arrangement being intended by me to duly correct and adapt the thrust of the piston and connecting-rod members from the 10 desired eccentric off-points of the axle-centers of said auxiliary driving-wheels so that they are elevated above the possibility of conflicting contact with any objects below the axle-centers of the said lower supporting-wheels, such improved arrangement of elevated auxiliary-drivers in connection with 15 said supporting-wheels bringing into effective action a lever-power that is in more direct line with the actual point of impingement or delivery of that power so as to materially enhance the use of the steam, decrease the undue size of the steam-cylinders, 20 increase the piston speed and the power of the lower supporting-wheels at the rails, and materially increasing the ratio of pressure 25 in the smaller cylinders from the generating boiler. It is my purpose herein to build a locomotive-engine that will develop most of its power at its most economical speed of 30 approximately five miles per hour. It is well known that all the large railroads use what are called "hump yards" and that, in such yards, engines are used that were designed to develop their maximum power and 35 economy at from twelve to fifteen miles per hour, on upgrades, of course, and that, with present methods of using such engines, they cannot be built to run slower and simultaneously develop more needed power for the 40 very obvious reason that their crank-pins would not have ample or proper clearance at the outer ends of the connecting-rods when the said outer ends are at the bottom of their down strokes, and their steam-cylinders are 45 abnormally large and cumbersome, with their piston-thrust unduly enormous and unreasonable, especially in view of the well-known fact that of said undue piston-thrust only a little over one-half thereof is actually applied to the track rail. The loss connected 50 with such a system is, of course, great and costly, and it is my aim to remedy it with my structure herein shown and described. It is my purpose, too, to materially reduce the size of the steam-cylinders and the piston-thrust whereby the piston-speed is increased 55 and, further, through the improved leverage system employed by me, the power at the point of contact with the track rail will be increased. Under present conditions, where the piston-thrust is applied to a single driving axle or shaft the piston-stroke must be shorter than the diameter of the driving-wheel, but, on the other hand, when the piston thrust is applied to an auxiliary, upper 60 driving axle or shaft, such as mine herein, the piston-stroke can be made longer than the diameter of the upper driving-wheel. 65 My improved structure herein comprises superposed auxiliary driving-wheels for locomotive engines that are supported on base wheels or rollers that have duly flanged rims or tires similar to the old form of driving-wheels, but without the weight of the engine 70 on the axles, the latter simply connecting the said base wheels or rollers in transversely-aligned pairs on the track and the load being borne by the axles of the said auxiliary driving-wheels whose rims properly conform 75 to and rest in frictional contact with the flanged rims or tires of said base wheels. The said upper auxiliary driving-wheels are provided with crank or eccentrically-set pins 80 that laterally extend from them for connection with the pitman of the sliding piston-rod 85 at each of the two longitudinal sides of the engine, but with ample clearance that is elevated considerably above any possible contact with the track or road-bed below. 90 In the accompanying several sheets of drawings, forming a part of this specification, the views are of a diagrammatic nature only, but they serve the full purpose of explaining my improved power-transmission system for locomotive steam-engines, and, 95 of such views, Fig. 1 is an elevation of a fragmentary part of the engine; Fig. 2, a transverse section of the track showing thereon in cross elevation my improved arrangement of lower supporting-wheels, and auxiliary 100 upper driving-wheels; Fig. 3, a side elevation showing my improved system herein, especially viewing a relatively small-sized upper auxiliary driver provided with a comparatively long crank-arm whose rod-connected end extends below the periphery of 105 said driver in the lowermost part of its 110

stroke and with ample clearance, way above any possible contact with the rail or the road-bed below; and Fig. 4, a side elevation showing a special form of lever system provided by me in the mounting of the upper auxiliary-drivers on the lower supporting wheels for the desired distribution of the weight and resilient pressure on the rims of the said lower supporting-wheels.

10 In these diagrammatic views, as above defined, I have shown only a very small fractional part of a locomotive steam-engine used in transporting cars along railways, but sufficient, however, to clearly illustrate (along 15 one side only) my somewhat simple invention herein that is adapted, more especially, to freight-carrying cars travelling at low or moderate rates of speed.

A indicates the track rails; B, one of the 20 two longitudinal elevated side rails or beams of the main-frame of the engine; B', the parallel top frame-rail; C, one of the usual two steam cylinders at the fore end of the engine; D, the piston within said cylinder; E, the 25 piston-rod; F, the sliding cross-head; G, the pitman or connecting-rod pivotally-connecting said cross-head and the outer end of a crank-arm H, and the latter radially-extending 30 from a horizontal drive-shaft I.

30 The drive-shaft I forms the main axle of each of the series of cross or transverse-axle-connected pairs of driving-wheels 7, which I have heretofore called auxiliary superposed driving-wheels because they are mounted in 35 the bearings or main driving-boxes 8 that are housed in the upper pedestals or housings 9 on the aforesaid main-frame rail B, the upper extremities of said housings being suitably attached to the said upper or top frame-rail B', as best seen in Fig. 4. Upright saddles 10 extend from the said main driving-boxes 8, and the horizontal sets of strong leaf-springs 11 are mounted in said saddles with their opposite ends pivotally-secured in the 40 upper ends of perpendicular hangers 12 and 12', the hanger 12 being, in turn, pivotally-secured at its lower end to the center of a horizontal equalizing-lever 13, and the other hanger 12' being pivotally-secured at its 45 lower end to the said main frame-rail B. In 50 said Fig. 4, it will be seen that the said equalizing-lever 13 has at one end a short extension-hanger connection 13' with the said main frame-rail B and at its other end a long lower 55 extension-hanger connection 14 with one end of a horizontal bar or lever 15 which passes in 60 intimate pivotal-contact with the bottom of the lower bearing boxes 16 at the opposite sides of the engine, the other or further end 65 of said lower lever 15 being pivotally-secured to the lower end of a short extension-hanger 17 that is parallel to the said long lower extension-hanger connection 14, and thence has 70 pivotal-connection with the said main frame-rail B.

Lower axles 18 connect cross-pairs of rollers or base supporting-wheels 19, the latter being mounted in vertical alignment with the said auxiliary superposed driving-wheels 7, and said rollers 19 are provided with flanges 70 20 along the inner edges of the preferably tapered peripheries of their tires or rims so as to conform to the flanged groove-extensions 21 provided along the reversed tapered rims of the said superposed driving-wheels 7, 75 as best seen in Fig. 2, whereby the desired frictional contact can be developed between the said superposed drivers and the lower or base supporting-rollers, the latter, in turn, then becoming transmission-drivers when in 80 contact with the track-rails.

The said lever-mechanism, comprising the said hangers, levers and springs, serves to draw or pull upward on the lower or bottom boxes of the engine so as to increase the pressure between the said main and lower bearing-boxes and the axles journaling therein, and thereby prevent the upper driving-wheels from slipping on the lower base supporting-wheels in the transmission of power from the 90 steam-cylinders to the track-rails. This lever-mechanism is an important feature of my invention herein and is essential to the successful transmission of said power from the steam-cylinders through the piston-thrust and 95 contacting pairs of upper and lower wheels onto the working-face of the track rails. Other forms of lever-mechanism for the desired frictional or other dependent transmission-contact of the upper and lower wheels 100 can be used in my improved locomotive structure, but that shown is believed at this time to be the best adapted to my purpose and is simple and effective in every practical way.

A lower frame-rail 22 is provided, parallel 105 to the main frame-rail B, beneath the lower bearing-boxes 16 and serves to duly support or stabilize the upright pedestals 23 of the said lower bearing-boxes in connection with said main frame-rail B and in due alignment 110 with the upper pedestals 9, as best seen in Fig. 4.

In Fig. 1 I have shown the pitman or connecting-rod as being coupled with the outer 115 end of a long crank-arm H that is mounted on the main axle of the upper driver, while in Fig. 2 I have shown a lateral crank-pin 120 24 extending from the upper driver direct, eccentric to its axle but not adapted to the same long leverage that the said crank-arm H affords in obtaining the greater stroke and power. A counternoise-extension 25 is provided on the said crank-arm H, as shown in Figs. 1 and 3, for its usual function. A greater range of variations in the piston-thrust of the engine is provided by the use of the said crank-arm members H on the upper drive-wheels and their axles and, in order 125 to further prevent the slipping of the upper wheels on the companion lower supporting 130

and transmission wheels, the weight of the engine might be proportionately increased and the piston-thrust on said crank-arms reduced to suit.

5 In Fig. 3, wherein I show my improved form of surmounted or elevated driver and its extended crank-arm H, together with a lower supporting power-transmission roller or wheel, and a comparatively small-sized 10 cylinder, the pressure in the cylinder is the same as that in the old form of cylinders, and the power at the rail is increased so that it will equal that of the piston-thrust when the stroke is equal to the diameter of the 15 upper drive-wheel. In said Fig. 3, the form of leverage simulates that of a second-class lever in mechanics, and it shows the connecting-rod coupled to the outer end of the crank-arm H, way beyond the peripheral line of 20 the upper driver, the latter being considerably smaller in diameter than that of the supporting roller or lower transmission-wheel and its delivery of power at the track-rail being slower but greater than if the ratio of 25 diameters were the reverse.

To sum up, in conclusion, with the past method of constructing a locomotive steam-engine, wherein the piston-thrust is applied to a single driving axle or shaft, the piston- 30 stroke must be shorter than the diameter of the driving-wheel, but, as in my present improvement wherein the piston-thrust is applied to an auxiliary superposed upper driving axle or shaft that carries the direct driving-wheel, the piston-stroke can be made 35 longer than the diameter of the driving-wheel and the power is materially increased with smaller cylinder-members and without danger of any contact of the elevated connecting-rod and crank-arm, or the crank-pin, 40 with the track or the ground, or with any obstructions below the level of the rims of the base supporting-wheels.

To prevent the engine constructed as herein becoming top-heavy and subject to toppling over, it is obvious that the lower supporting power-transmission rollers or wheels and the upper auxiliary drivers can be made proportionately small and yet secure the desired power at the track-rail, where needed, 45 50 in propelling the load.

In order to make the engagement of the upper auxiliary-drivers more positive than the friction-connection shown and described, it is quite obvious and possible that a gear-formation can be provided along the inner peripheral edges of the upper and lower sets 55 of wheels so as to intermesh and result in a no-slip transmission between the steam-cylinder and the track-rail contact. 60

I claim:

In a locomotive steam-engine, the combination of lower transverse-axle-connected flanged rollers or wheels forming a supporting sub-transmission base, a suitable engine-frame containing bearing-boxes, upper auxiliary driving-wheels having peripheral formations to coincide with the flanged base-wheels and also transverse-axle-connected in pairs so as to adapt them to be superposed 70 on said pairs of lower base-wheels, crank-arms extending diametrically from the axles of said driving-wheels in lengths to suit the desired stroke and piston-thrust, connecting rods or pitmen, sliding cross-heads, pistons, 75 steam-cylinders, and lever-equalizing mechanism comprising brackets and bars under spring-tension adapted to support and draw the upper auxiliary driving-wheels and the lower base-supporting wheels into co-relation 80 for the desired no-slip contact of the rims of said upper and lower sets of wheels, substantially as shown and described.

In testimony whereof I hereunto affix my signature.

WILLIAM H. BAKER, JR.
